UNITED STATES PATENT OFFICE

HEINRICH BERTSCH, OF CHEMNITZ, GERMANY, ASSIGNOR TO H. TH. BÖHME AKTIEN-
GESELLSCHAFT, OF CHEMNITZ, GERMANY, A CORPORATION OF GERMANY

EMULSION TREATMENTS AND AGENTS THEREFOR

No Drawing. Application filed June 20, 1929, Serial No. 372,550, and in Germany June 20, 1928.

Oils, fats and similar substances insoluble in water can be brought into the form of aqueous emulsions by the agency of soap solutions or Turkey red oils or by mixing said substances with superficially active aromatic sulpho-acids, such as propyl-naphthaline sulphonic acid. The stability exhibited by the emulsions so produced, is however, quite small; either they are comparatively highly sensitive electrolytically for instance in the case of the use of soap solutions as emulsifying agents, or they are incapable, owing to their low viscosity, of maintaining the dispersed particles sufficiently distributed in the liquid.

An attempt has been made to overcome the first defect by using electrolytically insensitive dispersion agents such as those constituted by the aromatic sulpho-acids. In attempting to counteract the second defect, the low viscosity, albumen decomposition products or gluey substances of the gelatine type have been added to the emulsions which were thereby rendered more stable. Finally dried and ground albuminous substances and the like have been mixed with the ground sodium salt of an aromatic sulpho-acid, such and similar mixtures being placed on the market as emulsifying agents. These emulsifying agents have, however, the one defect that they introduce an aromatic sulpho-acid into the system, a component which is often undesirable, particularly in applications involving the emulsification of oil for textile purposes.

According to the present invention the esters of the sulpho-fatty acids formed by the sulphonation of oils or their acids are employed as emulsifying agents for which purpose they have proved extremely suited. Such agents are useful in the preparation of emulsions of treatment substances for textile, leather and similar materials, metals and the like.

The esters in question are those of sulpho-fatty acids which are formed by the addition of a molecule of sulphuric acid to the hydroxyl group of hydroxy-fatty acids or to the double linkage of unsaturated fatty acids. Depending upon the circumstances the esterification may take place in the sulpho-

group or in the carboxyl group or at the same time both in the sulpho-group and in the carboxyl group.

Thus:—

Ricinoleic acid 55

$\text{CH}_3(\text{CH}_2)_5\text{CHOH CH}_2\text{CH}=\text{CH}(\text{CH}_2)_7\text{COOH}$;

gives on sulphonation sulpho-ricinoleic acid,

$\text{CH}_3(\text{CH}_2)_5\text{CHSO}_4\text{H CH}_2\text{CH}=\text{CH}(\text{CH}_2)_7\text{COOH}$ 60

esterification in the sulpho-group yields ricinoleic acid sulphuric monoester,

$\text{CH}_3(\text{CH}_2)_5\text{CHSO}_4\text{R CH}_2\text{CH}=\text{CH}(\text{CH}_2)_7\text{COOH}$ 65

and esterification in both the sulpho- and carboxyl-groups yields ricinoleic acid sulphuric diester,

$\text{CH}_3(\text{CH}_2)_5\text{CHSO}_4\text{R CH}_2\text{CH}=\text{CH}(\text{CH}_2)_7\text{COOR}$ 70

Three methods have proved feasible for the practical manufacture of these esters:—

(1) Sulpho-fatty acids produced according to known methods may be esterified with the desired alcohols; 75

(2) The alkyl sulphuric acid may be first prepared from concentrated sulphuric acid and the alcohol and the fatty acid introduced into the same under appropriate conditions; 80

(3) It has proved particularly simple and economical to carry out the addition of the sulphuric acid and the esterification in one operation. In this case the fatty acid is dissolved in the alcohol employed and the sulphuric acid then introduced. 85

The corresponding esters of the sulpho-acids with aliphatic or aromatic alcohol or phenol radicles of high molecular weight are, in part, more difficultly soluble, but, for example in mixture with agents facilitating solution, they are also good emulsifiers which, mixed with protective colloids such as albuminous substances, glues, decomposition products of such alkylated celluloses or other polysaccharides, constitute preparations capable of converting water-insoluble substances into perfectly fine and permanent dispersions. 95 100

Thus, for example, if 30 parts of a sulpho-fatty acid ester are mixed with 140 parts of glue-jelly, 1000 parts of mineral oil and 200 parts of water in, for instance, a grinding 5 or beating mill or homogenisator, then the end product is a very fine, uniform and permanent emulsion of mineral oil in water. Emulsions formed in accordance with the present invention will find use in many arts, 10 as for instance in lubricating, sizing and dressing.

I claim:—

1. The method of preparing an emulsifying agent comprising bringing together 15 an ester of a sulpho fatty acid and an organic colloid substance and agitating the mass sufficiently to form a homogeneous mixture.
2. An emulsifying agent comprising a sulpho-fatty acid esterified in at least one of 20 its groups and admixed with a protective colloid.

3. The method of preparing an emulsion of a liquid suitable for the treatment of textiles, leather, and similar materials, which comprises emulsifying the liquid with a mixture of an organic protective colloid substance 70 and an ester of a sulpho-fatty acid.

4. A wetting agent for the textile and allied industries comprising a sulpho-fatty acid esterified in the sulpho-group, and an organic protective colloid substance. 75

5. A wetting agent for the textile and allied industries comprising a sulpho-fatty acid esterified in the sulpho and carboxyl groups, and an organic protective colloid substance.

6. A wetting agent for the textile and allied industries comprising a sulpho-fatty acid ester in admixture with agents facilitating 80 solution in which the esterifying radical is of high molecular weight, and an organic protective colloid substance. 85
